United States Patent Office.

WILLIAM M. SMITH, OF WEST MERIDEN, CONNECTICUT.

Design No. 2,615, dated April 16, 1867.

DESIGN FOR A CASKET HANDLE.

The Schedule referred to in these Letters Patent and making part of the same.

TO ALL WHOM IT MAY CONCERN:

Be it known that I, WILLIAM M. SMITH, of West Meriden, county of New Haven, and State of Connecticut, have invented or produced a new and original Pattern or Design for Casket Handle; and I do hereby declare that the following is a clear and exact description of the same, reference being had to the photograph view, in which the same letters indicate like parts.

In the accompanying photograph view, A is a pattern of a handle plate configurated with a plain ornamental figure. B is a pattern of a handle configurated with a plain ornamental figure. The whole combined to produce a rich casket handle.

What I claim, therefore, and desire to secure by Letters Patent, is—

The design for a casket handle, substantially as above illustrated and set forth.

WM. M. SMITH. [L. s.]
